COMPUTER HOUSING

Theodore C. Sandborg, Los Angeles, Calif., assignor to Computer Research Corporation of California, a corporation of Delaware

Application February 26, 1953, Serial No. 23,810

Term of patent 14 years

(Cl. D64—11)

To all whom it may concern:

Be it known that I, Theodore C. Sandborg, a citizen of the United States, residing at Los Angeles, in the county of Los Angeles and State of California, have invented a new, original, and ornamental Design for a Computer Housing, of which the following is a specification, reference being had to the accompanying drawing, forming a part thereof.

Figure 1 is a perspective view of a computer housing, showing my new design;

Figure 2 is an elevational view of the end of the computer housing opposite that shown in Figure 1; and

Figure 3 is an enlarged section taken along the line 3—3 of Figure 1, illustrating the surface contour of the decorative border.

The opposite side of the computer housing from that shown in Figure 1 is the same as that shown in Figure 1.

The characteristic features of the present design are shown in full lines.

I claim:

The ornamental design for a computer housing, substantially as shown and described.

THEODORE C. SANDBORG.
